UNITED STATES PATENT OFFICE.

WILLIAM E. SMALL, OF BROOKLYN, NEW YORK.

HEEL-BUILDING MACHINE.

Application filed June 19, 1925. Serial No. 38,190.

My invention relates to heel building machines, and more particularly to a machine where lifts are selected and stacked in proper form for a particular style heel, each lift being glued to the other, then the mass pressed into a homogeneous heel structure after which they are discharged from the machine.

The invention is in the nature of a carrying forward the patent granted to me March 24, 1924, numbered 1,487,980. In said patent the lifts were assembled in proper formation and forced on a key by hand, as was the adhesive material, so as to form a particular style heel, after which manual means was employed to secure the initial pressure. The present invention is not only an improvement on all such means, but for a machine whereby its mechanism is simple, cheap and automatic, thereby accomplishing a result with a better, more perfect and greater production.

An object of my invention is to have a central pedestal on which will revolve intermittently a member, provided with a plurality of circumferentially arranged assembling devices adapted to receive on a means, a stack of selected lifts in superposed relation, each lift being glued one to the other, then applying pressure to the stacked mass before they are discharged. The revolving member is given a step by step intermittent movement, allowing only the necessary time for the operator to assemble the proper number of lifts to make the predetermined height heel. For instance, the machine has two sources of power, one to act upon the horizontally revolving member and the other for operating the vertically reciprocating lift assembling mechanism for stacking the lifts into mass formation of a proper height, first, the several lifts of various sizes to form a particular style heel are stacked and glued in position on the key, second, the revolvable manner is then moved a step when the stack of lifts receive its necessary pressure. At a predetermined point the pressure is released, the presser foot raised, the key extracted and the stack released from the equalizer, and lastly the built-up heel discharged from the assembling device. After which the key is again automatically moved in position and the assembling device placed again in front of the operator to assemble another stack of lifts to form a particular height heel.

Another object of my invention is, to provide a suitable number of heel assembling devices arranged about the circular revolving member, whereby the same will be in its extended position when it arrives in front of the operator. Each assembling device receives a suitable number of selected lifts of various sizes and shapes for either a flat or inclined heel of a particular style and height, each lift not only being locked to the preceding one, but each being in addition glued to the other lift, so as to form a perfect heel of a predetermined style and height. Each and every time a mass of lifts have been assembled and glued in superimposed relation in the assembling device, each of the various preceding built-up heels are undergoing various processes in the continuous production of the built-up heel while its revolving member is making a complete revolution.

Still another object of my invention is to provide a machine whereby the operator sits in front of the machine and has within his or her reach lifts of the various sizes to build heels of a given height and design, and after each built-up mass of lifts are stacked to the proper height, the same is moved one step in its travel, as has been noted, to allow another empty assembling device to come before the operator. A calibrated scale is operated by the lift assembling mechanism, whereby the operator may see at a glance the particular height of the lifts that have been so far assembled.

With the foregoing and other objects in view, further objects and advantages will appear as the description of the invention is hereinafter developed.

Referring to the drawings wherein is shown what is now considered to be the preferred form of my invention—

Fig. 1, is a partial front view of my heel-building machine with its mechanism, some parts broken away and others omitted for clearness.

Fig. 2, is a front view of the heel assembling device, showing the non-revolvable top that carries the pressure regulating devices, the lower part being omitted for clearness.

Fig. 3, is a vertical sectional view of the same, showing the friction means applied to the presser foot, also means for adjusting the equalizer for building certain kinds of heels.

Fig. 4, is a side view of the assembling mechanism, and the gluing mechanism sep-

arate from the rest of the machine, and some other parts omitted for clearness.

Fig. 4^A is a sectional detail of the driving gear from the motor to the assembling device.

Fig. 5, is a face view of the calibrated gauge for indicating the number of lifts or height that has been placed on the equalizer.

Fig. 6, is a top plan view of the glue brush carriage, showing the brush in position as it applies the glue to the top lift.

Fig. 7, is a side view of the top of the pedestal, showing the hand operating means for regulating the distance between the pressure plate and the top of the selected mass of lifts.

Fig. 8, is a horizontal section of a portion of the mechanism for advancing the gluing element, showing the handle for releasing the brush from operating when the last lift has been placed.

Fig. 9 is another horizontal sectional view, showing cooperating mechanism for operating the glue brush.

Fig. 10 is still another horizontal sectional view on lines 10—10 of Fig. 1, showing the vertical carriage and adjusting means for centering the various cooperating parts.

Fig. 11 is a detail view showing the cam and lever for operating the glue pump that feeds the brush.

Fig. 12 is a detail perspective of the gluing mechanism, also the lever for pressing the brush down to apply the glue to the lift.

Figure 12^A is a top plan view of the brush showing the perforations through which the glue is conveyed to the bristles of the brush.

Fig. 13 is a top plan view of the carriage holding the glue brush, showing the means for advancing and returning the brush.

Fig. 14 is a portion of my machine showing means for applying and releasing the pressure on the built-up mass of lifts, also showing camway for extracting the key from the slot in the built-up mass of lifts.

Fig. 15 is another portion of the machine showing the key totally withdrawn, the heel releasing device operating, and the kicker device ready to discharge the finished product from the machine.

Fig. 16 is a view showing a portion of the revolvable member, and the cams beneath the same for extending the receiving devices, and at the same time extracting the key while the device is making one of its step movements.

Fig. 17 is a side view of the power means for turning the revolvable member.

Fig. 18 is a plan view of the cam for starting and stopping the machine.

Fig. 19 is a vertical sectional view of a heel built up by various size selected lifts to the desired height; and

Fig. 20 is a top plan view of the lift, showing the key-way in the same for holding the mass in proper cooperative relation while being assembled and pressed into a heel.

Like characters of reference designates same parts throughout the several views of the drawings.

As is well known in the trade, some heels are nailed to hold the various lifts that form the same in stack formation, in which case they cannot get the same pressure to the lifts that may be applied to those that are glued, because of the fact, first, that if a full length nail is used, it will take the pressure that should be received by the various layers of lifts; or if the nail is too short, then the lifts will not all be held together in mass formation.

Again, should a heel be built by hand or by device in anything but a perfect manner, even should the imperfection be of a very slight degree, will, when it is placed in the compressor, be aligned all right; but in doing so, the glue that is holding the lifts together becomes cracked and broken, with the result that when taken from said compressor the heel will be defective, causing loss of time and labor.

The machine as constructed and operated comprises a central pedestal having thereon a stationary and a movable member, each member having coating and cooperative parts that are brought into action by reason of the movable member being moved by the prime mover (not shown).

When the operator presses the lever 103 downwardly the link 152 is removed from the depression 153' in the stop cam 153. To the upper face of the cam is secured a ratchet and pawl mechanism 154, which operates the shaft 155, the latter having on its opposite end a gear 156

which meshes with a like gear 157 that is on the movable member 22. By pressing this lever 103 it starts the movable member on its degree of intermittent rotation. The motor being so geared to the movable member as to move it at the proper speed to allow the various cooperating devices to perform their respective operations while so moving.

Again, the motor moves the movable member only as far as is required to bring the next assembling device in front of the operator. Then as the operator presents each lift to the key in the assembling device the lever 101 is pressed downwardly which causes the motor A to operate the heel cooperating parts, causing each of the various devices connected therewith to perform their respective cooperative action until the complete number of lifts have been assembled to form a heel.

My improved heel building machine comprises a central pedestal 21, having a revolvable member 22, and a non-rotating member 23; the latter having a suitable hub 24, with extending strengthening ribs 25, that provide a very strong resisting plate for the parts that cooperate therewith.

On the top of the pedestal 21 is a hand wheel 26, provided with suitable means for raising and lowering the non-rotating mem-

ber 23, and the parts that are attached thereto. The top of the pedestal is provided with a calibrated scale 27, which has an indicating finger 28 on the hub 24 of the non-rotating member, so that the operator may set the exact distance the non-rotatable member should move for a heel of a given height. For instance, as shown particularly in Fig. 7, when it is desired to build a heel of eight lifts, or 8 eighths, as termed in the trade, the hand wheel 26 is turned until the indicating finger 28 registers on the scale for the 8 eighths.

By this means, the required adjustment is made to the non-rotating member, so that when the rotatable member with its assembling devices come under the various devices carried by said non-rotating member, that the heel carried therein will get the desired pressure from the device.

Referring now to Fig. 1, wherein is shown my main operating device, it being understood that a motor A provided with a starting and braking mechanism will be placed on top of the non-rotating member 23. The shaft 29, which carries a main driving cam 30 having a closed way 31 therein, and into which is fitted to operate a roller 32, carried by a vertically reciprocated member 33 forming the upper part, and 34 the lower part, which latter carries the mechanism for completing the building up of the lifts into the heel. To the outer end of shaft 29 is a worm 29' enclosed within a casting 35, which also houses a suitable wheel 36' shown in Figure 4^A; the shaft 36 of the latter is squared at its upper end so as to permit the carriage to be reciprocated, while the worm revolves the shaft.

The reciprocative members 33 and 34 are normally connected together by two rods 37 and 38, the latter making the full stroke of the upper member 33, while the lower member 34 is only resiliently secured to the lower end of the rods 37 and 38, springs 39 interposed between the member 34 and the collars 40, permits the member 34 to be arrested while the member 33 and rods 37 and 38 are making their full stroke.

Referring now to the receiving devices into which the lifts are assembled, see Figs. 4 and 5, it will be seen, as above noted, that the lower member 34 carries two lift pressure fingers 41 and 42, which are adjustably secured to a movable slide 43, which may by reason of the hand wheel 44, be adjusted longitudinally so that the fingers press the lifts down as they are presented manually by the operator on the key 45. As the cam 30 causes the member 34 to reciprocate, the fingers 41 and 42 do also; but as each lift is placed on the key 45, the fingers arrest the lower member 34 from further downward movement. As noted, as each lift is placed in position on the equalizer, the member 34

is arrested from further movement by the fingers 41 and 42 resting on the top lift, the calibrated scale 46 carried by the lower member 34 is also arrested, while adjacent to the scale is a movable slideable bar 47, on which is secured an indicating member 48', operating over the face of the scale 46. The counting or indicating device comprises a spherical chamber 48', tapering as it reaches its lower end, and into which is held a spring 49 that abuts against the screw 50, and against the ball 51. In addition to the above, an adjustable gauge 52 may be secured to the stationary member 34, while the movable member 48' carries a tooth 52' that is adapted to engage the part 52, which parts are connected with the audible signal showing that the predetermined number of lifts have been applied. As will be seen, since an arm extends from the rod 37 to the rod 47, the former causes the said bar to take the full stroke of the member 33, while the lifts placed in the receiving member arrest the scale, and the difference in the movements of each registers on the scale 46. Thus, for every lift that is placed on the key 45, the counting device just referred to will register the height the heel has been built. On the lower end 156 of the bar 47 is a spring 157 which urges the member 48' upwardly to return the indicator member 48 to its normal position.

A handle is pivotally arranged whereby, after each heel has been built to its desired height, the operator presses the handle and the indicating finger will return to zero.

The gumming device is one of the essential devices of my machine, and presuming that the fluid is of the proper consistency for perfect operation, a reservoir is provided for holding a suitable quantity of the glue in a convenient place, so as to be fed to the machine in quantities as may be needed. Referring to Figs. 10 and 12, wherein is shown the gluing system detached from the other cooperating parts, and its operation is as follows:

For every revolution of the shaft 29 the cam 30 will revolve the driving means so as to cause the shaft 36 to revolve. Said shaft carries a cam 53, that causes the lever 54 to raise and lower at proper times. Said lever is hinged to the top of the lower reciprocating member 34, in ears 55, and extends rearwardly and rests on the top of a plunger rod 56, the latter having a roller 57 thereon, so as to give as little friction as possible. The rod 56 passes through a small pump 58, which causes the glue to be forced from the source of supply through pipe 59, to a small reservoir 60, where in turn it is forced through a flexible pipe 61 down to the brush. The latter is provided with a suitable receptacle 62 for holding a small quantity, and through openings 63' in the top of the brush 63, permits the fluid to saturate the bristles of the

brush and thus the lifts when contact is made.

The operation of the brush is as follows: Referring to Figs. 8 to 13 inclusive, it will be seen as the cam 30 causes the upper and lower reciprocating members 33 and 34 and their co-acting parts to descend, and as the shaft 36 revolves, it causes the cam 53 to revolve, at the same time cam 64, which is on the lower end of said shaft. Suitably mounted on a short shaft 65 is an arm 66, having at its free end a roller 67, to operate with the cam 64, which arm operates a handle 68 having a latch 69, the latter being hinged at 70.

Secured to the shaft 65, below the handle 68, is a gear segment 71, loosely mounted on said shaft, which meshes with another gear segment 72 on a shaft 73. The former segment is provided with suitable actuating springs 74, to return the parts to their proper position of rest after being operated. Said gear segment 71 has a body portion 75, which may be provided with a notch 76, or other equivalents, to receive the end of the latch 69, where it may be provided with a stop for the handle. The gear segment 72 has a heel 77, provided with a regulating screw 78 and a nut 79, so that the proper movement may be provided for the shaft 73, by its contact 30. with the projection 80 on the lower member 34.

It will be understood that when the latch 69 is in the notch 76, the segment 71 will operate segment 72 on shaft 73. To the lower end thereof is secured a lever 81, having a slot 82, which operates a pin 83, on a slide 84 carried by the member 34. Thus, as said shaft is operated by the segments to force these parts forward, the springs will return 40 the same to their rearward or normal inoperative position. The slide 84, which carries the brush, on its extreme forward movement, moves the brush operating mechanism into contact with an adjustable screw 85, see 45 Fig. 4, held in a lug on the member 34. Said screw trips the lever 86, mounted on a short spring pressed shaft 87, carried by the brush holder. On the lower side of the slide 84 is a small bracket 88, which engages a hooked 50 lever 89 on the shaft 87. The brush holder has on each side an arm, 90 and 91, through which guide bars 92 and 93 extend, and about the latter are preferably secured coiled springs 94 and 95, held between the slide 84 and the arms 90 and 91. Thus it will be 55 seen that as soon as the arm 86 is tripped by the screw 85, the latch lever 89 will be released from the bracket 88, and the springs 94 and 95 will force the brush with its contents of glue down. At this point the brush when it is tripped is over the lift that has been forced down on the key by the fingers 41 and 42. Consequently when the brush 63 is lowered the lift is applied with paste, 60 then as the arm 81 draws the slide 84 back, 65

it draws the brush with its adhesive material across the top lift, and leaves thereon a deposit of glue for the next lift to be forced down upon. Thus when the brush is returned to its rearmost position the lever 54 is 70 on the low side of the cam 53, and as it returns to its position of rest, the lever 54 is depressed by the roller 57 riding up on the elevated side of the cam. In doing so, causing the shaft 56 to be depressed and thereby 75 pressing on the free end of a lever 96 to elevate the brush 63, the pivot 97 permits of the elevating and depressing of the brush.

Referring to Fig. 4 it will be seen that the reciprocating member 34 is provided with another dove-tail slide 98, whereby the fingers 41 and 42 may be adjusted by a hand wheel 99 transversely of the member 34, so that the fingers under any and all circumstances may be adjusted to their proper position with relation to the key 45, on which the lifts are held.

Each and every time the operator places a lift in position over the key 45, he or she presses a pedal 101 connecting by link 102, to the motor A on the non-rotating member, causing the cam 30 to revolve and the member 33 to reciprocate vertically on its guide bar 100, thus by this movement causing each co-operating part to function, and as has been seen, as each lift is selected and assembled in stack formation on the key 45, the member 34 moves less and less vertically, according to the number of lifts placed in the device. Each time the fingers 41 and 42 push a lift on the key 45, the height thereof is registered on the scale 46 till the desired height of the heel has been stacked.

When the predetermined height of the heel has been reached the operator presses a pedal 103 and the revolvable member with the receiving device moves a predetermined distance by the power mechanism 104, where the last filled receiving device is brought under the first of the pressure regulating devices on the non-rotatable member, and is retained there while the operator is building the next heel. Only a part of the power mechanism is shown, and description thereof will be given further on.

Thus we have seen that the heel operating mechanism is entirely held stationary in front of the machine without interfering in any way with the revolvable member that carries the several assembling devices. The latter comprises a breast plate 105, so curved to fit the breast of the heel and has on its inner face the key 45, operating in a way 106. Said key on its lower end has a bearing rod 107, passing through a bearing 108 on the lower outer face of the breast plate. Said rod has a cam head 109, provided with a finger 110 that operates in the cam path between faces 111 and 112, the former being in the nature of a closed cam, while the latter is simply a slide whereby the 115 120 125 130

finger forces the key 45 back in proper position to again receive another stack of lifts. Said bearing 108 is also provided with a suitable spring 113, while the head 109 has a 5 suitable recess into which said spring snaps and holds the key always in position till again operated upon by the cams 111 and 112.

Referring particularly to Figs. 2 and 3, it will be seen that the breast plate 105 may be 10 provided with a rearwardly extending base 114, having outwardly extending guide flanges 115 and 116, the latter being housed in the revolvable member 22. The base plate 114 near its forward end has a cut away part 15 117, and is provided with a slide having graduated steps 118. Said movable slide is adapted to be moved rearwardly when an inclined heel is desired. An equalizer 119 having a pointed forward end 120 that rests under the 20 curved breast 106, which holds it in position, the under side of said equalizer is provided with a foot 121, to which may be secured one or more adjusting thumb nuts 122 for holding the equalizer in any predetermined position, 25 according to the style of the heel to be built.

Said equalizer 119 may have any desired depth of plate 123 secured thereto, so as to give the heel a more or less cupped depression. Suitably secured to the base 114 is another 30 bearing 124, extending from the assembling device, having a pin 125, operating therein. Said pin has a collar 126, which permits of its top being below the cupping plate 123, while its lower end is adapted to engage a 35 stationary guide plate 127. Thus it will be seen from Figure 15, about the same time the key 45 is extracted from the built up stack of lifts, the plate 127 will cause the pin 125 to move vertically and thereby elevate the built 40 up heel slightly, thereby loosening the heel should any of the glue have leaked over the lift to the equalizer. By so releasing the built-up heel from the equalizer, it will be an easy matter then, as the revolvable member turns 45 to its next position, for the kicker 128 to dislodge and discharge the same. To the pressure member 23, is secured a bracket 129, and pivoted to the latter is a kicker arm 130, pivoted to the bracket at 131, and provided at its 50 upper part with a slotted end 132, while the bracket is provided with an ear 133, into which is housed one end of a rod 134, the other end extending through said slotted end 132 and having a head 135 thereon, while between the ear on the bracket and the slotted end of the kicker arm is a suitable spring 136, that yieldingly engages the heel and discharges the same as the revolvable member 55 passes said kicker.

The revolvable member 22, as is shown in Fig. 1, consists of two parts, one above the other, separated by suitable spacing arms 137. The lower part of the revolvable member carries a plurality of receiving or assembling devices 105, while the upper part car-

ries a presser foot 138, provided with a stem 139, passing through the upper part of the revolvable member, and is provided with a wheel 140. The stem may be provided with a stop 141, so as to regulate its lowermost position. In the face of the upper part of the revolvable member is a friction lock, comprising a curved face stud 142, having a leather or other suitable substance 143, between the same and the stem 139, while a screw 144 provides the proper pressure on the stem to hold it in any of the several positions it may assume by reason of coming in contact with the pressure devices, that will now be described.

As soon as the proper height of lifts has 70 been stacked in the receiving device to form a particular style heel, and the operator presses the pedal 101, the revolvable member starts and moves a predetermined distance or one step in its travel; as soon as it does, the 75 wheel 140 encounters the inclined block 145, which is suitably secured on its inclined end by screw 146, while its inner end is provided with an upwardly extending pivoted rod 147 passing through pressure plate 23, and 80 through a collar 149 and a yoke 149', secured to the top of said plate. Said rod has a suitable adjusting means 150 to regulate the 85 downward pressure that the springs 151 exert upon it. The nuts 150 with the yoke 90 149' regulates the spring pressure desired on a particular built-up heel.

The friction means on the stem 139 obviates the necessity of having a continuous pressure plate, which at all times would be in contact with the wheels 140. With my improved means, suitable pressure may be made with one device 145, or such blocks may be arranged to give successive pressures to the heel as it passes thereunder.

Referring to Figs. 14 and 16, it will be seen how the pressure block 145 presses the presser foot 130 down on the built-up mass, and after having passed the final pressure device 145, how the heel, by a further movement 100 of the revolvable member, brings the roller 140 on its next step from the pressure block to the releasing cam 152, which is also secured to the under side of the pressure plate 23, and in path of the rollers 140. As the rollers 110 pass along this plate, lifting the presser foot from the stack, the finger 110 is trapped by the faces of bars 111 and 112 which then extracts the key from the stack, and on a further movement by reason of the projection on the receiving device coming in contact with an outwardly extending cam 151', extending beneath the revolvable member, causes the receiving devices to be extended to their extreme length, where it remains; and by a further movement the key is again inserted in place for further building by the operator.

By reason of the edges of the key being made knife edged it is only necessary to make 130

the key-way in the various lifts in the form of a notch, the fingers 41 and 42 insuring the various lifts being forced down on the key, where they will be held against all pressures that may be exerted in any direction, without getting out of alignment. In other words, this machine builds heels of a predetermined style, in such alignment that when the product is placed in a mold that fits that particular heel, it is held therein while the final cupping is being formed. A type of heel lift adapted for manipulation in my machine is shown in Figures 19 and 20, and has a body 159 and a key notch 160.

Thus it will readily be seen that the employment of my machine for building heels will not only perform automatically what has heretofore been done by hand, but will be able to perform the operations in a much more rapid rate, and much more effectively than has heretofore been done by hand.

From the foregoing it will be seen that I have provided a construction which is simple and effective, and whereby the lifts are not only assembled into a mass to form a heel, but that the mechanisms are all arranged to work automatically, following the method disclosed in my hereinbefore mentioned patent.

According to the provisions of the patent statutes, I have described the principle and operation of my invention, together with the construction which I now consider to be the best embodiment thereof. However, I desire to have it understood that the machine, as shown, is only illustrative and that the invention can be carried out in other ways than those described. As, for instance, it may be noted that an alarm may be provided so that when the desired or predetermined height of the heel had been attained, that a bell would be sounded and thereby obviate the necessity of the operator watching the scale 46, at all times; or would be a means of attracting the attention of the operator at the particular time when the number of lifts had been stacked to the desired height.

What I claim as new is:

1. The combination in a heel building machine, of a pair of members, one being movable with respect to the other, receiving units on said movable member for lifts of heels to be built and each including a key element for centering the respective lifts, a movable frame carried by the other member, means for advancing the movable member to dispose the various receiving units successively beneath the frame, means carried by the frame for pressing each lift on the key of the unit therebeneath, and a power element for actuating said frame to move it toward and away from each receiving unit.

2. The combination in a heel building machine, of a pair of members, one being movable with respect to the other, receiving units

on said movable member for lifts of heels to be built and each including a key element for centering the respective lifts, a frame carried by the other member and adapted to reciprocate toward and away from the movable member with a step-by-step intermittent motion to dispose the various receiving units successively beneath the frame, a power element for actuating said frame, and means carried by the frame for pressing each lift on the key of the unit therebeneath. 75

3. The combination in a heel building machine, of a pair of members, one being movable with respect to the other and spaced therefrom, receiving units on said movable member for lifts of heels to be built and each including a key element for centering the respective lifts, an adjustable frame carried by the other member and adapted to reciprocate toward and away from the movable member, means for actuating the movable member with a step-by-step intermittent motion to dispose the various receiving units successively beneath the frame, a power element for actuating the frame, and adjustable 85 means carried by the frame for pressing each lift on the key of the unit therebeneath. 90

4. The combination in a heel building machine, of a pair of members, one being movable with respect to the other, receiving units on said movable member for lifts of heels to be built and each including a key element for centering the respective lifts, a sectional frame carried by the other member and adapted to reciprocate toward and away from the movable member, means for actuating the movable member to dispose the receiving units successively beneath the frame, means for actuating the frame, means carried by the frame for pressing each lift on the key of the unit therebeneath, and one section of the frame being yieldable with respect to the other thereby to compensate for the difference in the length of the stroke of the frame and the height of the stack of lifts manipulated on the key by said last mentioned means. 95 100 105 110 115

5. The combination in a heel building machine, of a pair of members having a common vertical axis, one being rotatable with respect to the other, receiving units on said rotatable member for lifts of heels to be built and each including a key for centering the respective lifts, a sectional frame carried by the other member and adapted to reciprocate toward and away from the rotatable member, means for actuating the rotatable member to dispose the receiving units beneath the frame successively, means for actuating the frame, adjustable means carried by the frame for pressing each lift on the key of the unit therebeneath, and one section of the frame being yieldable with respect to the other thereby to compensate for difference in length of the stroke of the frame and the 120 125 130

height of the stack of lifts manipulated on the key by the last named means.

6. The combination in a heel building machine, of a pair of members one adapted to 5 rotate with respect to the other, receiving units carried by one member for lifts of heels to be built and including an adjustable support for the lifts and a key element for centering the lifts thereon, a reciprocable frame 10 carried by the other member, means for advancing one member with respect to the other to successively dispose the receiving units below the frame, means carried by the frame for pressing each lift on the key of the unit 15 therebeneath, and means on the frame for limiting the stroke of said aforementioned means to the height of the successive lifts placed on the receiving unit.

7. The combination in a heel building machine, of a movable member for receiving at 20 intervals thereon lift assemblies for heels to be built, a key element for each assembly, a reciprocating frame, means for advancing the movable member to successively position 25 the lift assemblies below the frame, means carried by the frame for pressing the respective lifts on the key elements, a power element for actuating the frame, a pump unit connected with the power element and with a 30 source of supply of adhesive substance, a brush connected with the pump, and means connecting the brush with the power unit for moving the same across each lift subsequent to its disposition on the key element by 35 the pressing means therefor.

8. The combination in a heel building machine, of a pair of members, one adapted to 40 rotate with respect to the other, receiving units carried by one member for lifts of heels to be built and including an adjustable support for the lifts and a key element for centering the lifts thereon, a reciprocable frame carried by the other member, means for advancing one member with respect to the other 45 with a step-by-step intermittent motion to successively dispose the receiving units below the frame, means carried by the frame for pressing each lift on the key of the unit therebeneath, said frame being formed with 50 yieldably connected sections thereby to compensate for the difference in stroke between the frame and the limit of movement of the lift pressing means as determined by the height of the stack of lifts in the receiving 55 device.

9. The combination in a heel building machine of a pair of members arranged on a pedestal common to the two, one stationary thereon and the other rotatable with respect 60 thereto; a power element journalled on the fixed member, a power element associated with the rotatable member to give it a step-by-step intermittent motion, a plurality of heel lift receiving members spaced circumferentially on the rotatable member and each 65

provided with a centering key, a fountain brush carried by the fixed member, a pump unit having connection with the fountain brush and a source of adhesive substance supply, a frame on the fixed element carrying 70 means for pressing lifts upon the centering keys, and the frame, the pump, and the fountain brush having operative connection with the power element on the fixed member whereby the brush is given a wiping motion across 75 the surface of each lift after it has been pressed upon the key.

10. The combination in a heel building machine of a pair of members arranged on a common vertical axis, one of said members being stationary and the other movable with respect thereto; a reciprocable sectional frame carried on the fixed member, said sections being yieldably connected to give upon meeting resistance in the path of the travel 80 of the frame in one direction, measuring means to indicate the amount of give in any one stroke of the frame, heel lift receiving devices on the rotatable member each having a centering key, adjustable fingers on the frame for pressing lifts on the respective keys, the height of said lifts being measured by the give induced by the obstruction afforded by contact of the fingers with the top of the stack of lifts, and means whereby the stationary member may be adjusted with respect to the rotatable member to vary the normal stroke of the frame, said means being provided with an indicating device operably 85 associated with a fixed base.

11. In a heel building machine, the combination of a stationary and a rotatable member, the rotatable member carrying at intervals thereon lift assemblies for heels to be built, a key element for each assembly, a reciprocating frame, means for advancing the rotatable member to successively position the lift assemblies below the frame, means carried by the frame for pressing the respective lifts on the key elements, a stationary member carrying means for gluing each lift to its next adjacent lift in a stack, means for pressing each stack of lifts, and means carried by the stationary member and engaging the pressing means for gradually increasing the 90 pressure on the stack after the same has been completed and the lifts glued, and other means independent of the aforementioned means and also carried by the fixed member 95 for positively releasing the pressing member 100 from the stack.

12. The device as described in claim 11, and means simultaneously effective with the aforementioned means for releasing the pressing means for withdrawing the key from each stack.

13. In a heel building machine, the combination of a stationary and a rotatable member, the rotatable member carrying receiving 110 units for stacks of heel lifts; a fountain brush 115

- carried by the stationary member and swingably mounted for wiping movement across the respective lifts, a pump element connected with the frame and with a source of adhesive substance supply, a power device, a shaft from the power device, and a pair of cams, one adapted to actuate said pump element and the other adapted to swing said brush for the purpose defined.
14. In a heel building machine, the combination of a stationary and a rotatable member, the rotatable member carrying receiving units for stacks of heel lifts, and the stationary member carrying a reciprocating frame provided with fingers for manipulating said lifts; a fountain brush carried by the stationary member and mounted for wiping movement across the respective lifts, means for supplying adhesive fluid to said brush, and a power device having a pair of shafts, one operatively connected with the other, one of said shafts having a single cam adapted to reciprocate the frame, and the other shaft having a pair of cams set to function in sequence after the first cam and associated with the adhesive supply means and the fountain brush whereby the lifts are assembled and the adhesive fluid applied to each lift as it is placed in position in its receiving unit.
15. In a heel building machine, the combination of a stationary and a rotatable member, the rotatable member carrying receiving units for stacks of heel lifts and the stationary member having devices for manipulating the respective lifts to form the stacks; means carried by the rotatable member for loosening a stack of lifts when assembled, and independent means carried by the stationary member and including an automatically functioning kicker for removing completed stacks of lifts from the receiving units after they have been loosened by the first mentioned means.
16. In a machine of the class described, the combination of a pedestal having a top plate adjustably mounted thereon, an automatic step by step revolving member on the pedestal below the top plate and having receiving devices for heel lifts spaced circumferentially thereon, said receiving devices each provided with an adjustable equalizing support, an automatically movable means for receiving and holding the lifts in stack formation, means carried by the top plate for applying paste to the lifts, means for automatically advancing said pasting device to paste said lifts as they are stacked, automatic means for applying pressure to the built-up mass, other means for holding said means to the degree pressed, devices for withdrawing the automatic movable means and extending the receiving device, and means for discharging the finished product from the machine while moving to its first or original position.
17. In a machine of the class described, the combination of a pedestal, a revolvable and a non-revolvable part mounted thereon, means for adjusting one with relation to the other, an indicator to regulate the adjustment, movable receiving devices arranged radially about the revolvable part, a key for holding lifts one upon the other in stack formation in the receiving devices, a brush for applying glue to the lifts, means for advancing the gluing brush to deposit glue on each lift as placed in position, means for applying pressure to the mass, means for retaining said pressure, separate power means for operating each mechanism and stationary devices for releasing the pressure, withdrawing the key, and extending the receiving devices while the revolving part is moving to its first or original position.
18. In a machine of the class described, the combination of a pedestal, a revolvable and a non-revolvable part mounted thereon; means for adjusting one with relation to the other, receiving devices arranged about the revolvable part adapted to move radially to receive a number of lifts to form a particular height of heel, an equalizing support on each receiving device and provided with a cupping plate, operating means for placing the selected lifts on a movable retained device, such device automatically operated; an automatically operated glue applying device, other means for operating the gluing device to cement the stack of lifts into mass formation, a presser foot, means for applying pressure to the presser foot, means for holding said pressure after passing the first said means, and means for operating both mechanisms simultaneously, releasing the retainer for the lifts, radially extending the receiving devices as they reach a predetermined point to discharge the built-up product.
19. In a machine of the character described, the combination of a revolving element, a regulating element, receiving elements, radially disposed with means for securing lifts one on another, a gluing element to cement the several lifts as laid into a solid mass, means for applying pressure to said lifts, devices for regulating the pressure on said mass and holding the same after passing said devices, separate means for releasing said pressure, a cooperative device for extending the receiving element and extracting the lift securing means simultaneously with the movement of the revolving element preparatory to the discharge of the finished product.
20. The combination in a machine of the character described, of a horizontally disposed revolving member, a vertically movable member, adjustable means for regulating the latter, movable receiving members on the revolving member, a drive shaft journalled in the vertically movable member and having a cam, a member reciprocated by the same, arms on said member supporting a second member, lift pushing fingers adjustably secured to the same, yielding means be-

- between the two members, whereby its movement is arrested by the height of the lifts, an adhesive applying means adapted to advance above the lifts, means for permitting 5 said means to move down upon the top lift and apply an adhesive to the lift, means for returning it to its former position, and means for elevating and locking the same in its elevated position, adjustable spring pressed 10 cam block for causing the initial pressure on said vertically movable member, means for holding the said pressure while passing to the next pressure block, and power means operating alternatively on the drive shaft and 15 the revolving member.
21. The combination in a heel building machine, of a pair of members, one being movable with respect to the other, receiving units on one of said members for lifts of 20 heels to be built, a frame, means for advancing the movable member to dispose various receiving units beneath the frame, means carried by the frame for centering each lift on the receiving unit therebeneath, a power unit 25 for actuating said frame to move it toward and away from each receiving unit, and an indicating device in conjunction with said frame for determining the height of the heel to be built.
- 30 22. The combination in a machine of the class described, of a drive shaft mechanism having thereon a cam, a reciprocating member operated thereby, said member being in two sections, one yieldingly held with respect 35 to the other, lift pushing fingers carried by the yielding member, adjusting means for said fingers, a glue applying brush adapted to be moved forward and downwardly to apply glue to the top lift, means for returning and 40 raising the same, and power driving means for the operating of the various parts.
23. The combination in a machine of the class described, of a revolvable structure having lift receiving members, each provided 45 with a retaining device, a vertically movable member located above, and stationary cooperating devices below said revolvable member, a drive shaft on the vertically movable member and having thereon a cam, a two part 50 reciprocating element, means protruding from said last named element for pushing lifts on the retaining device carried by each receiving member, an adhesive applying means adapted to advance above the stack of 55 lifts, means for preventing the same from moving down upon the last lift and permitting it to return elevated to its original position; means above and below the revolving member for causing and removing the pressure 60 on the mass, and power means for operating alternatively on the drive shaft and the revolvable member.
24. The combination in a machine of the class described adapted to receive and hold 65 a stack of lifts to form a heel within a receiving device; of a revolvable member carrying the receiving device, means for applying pressure to the built-up mass, a holding and a retaining element in such device; means for imparting intermittently rotating movement 70 to the revolvable member, and means for relieving the pressure from the mass of lifts when said member is at a predetermined point while in motion and for discharging the product so formed preparatory to moving 75 the receiving device to its original or starting position.
25. The combination in a machine of the class described, of an adjustable top plate, a plurality of adjustable pressure devices 80 thereon, a rotatable member, a plurality of extensible receiving devices thereon and each having a centering key, a lift operating mechanism comprising fingers for placing the lifts on the key, a height indicating means and a 85 gluing mechanism operating simultaneously therewith; means for releasing the pressure, stationary means for extending the receiving devices and extracting the key, other means for loosening the built-up mass and discharging 90 the finished product from the machine while the same is making a step movement, and power means whereby the revolvable member and the lift operating mechanism 95 are alternately operated.
26. The combination in a machine of the class described, of a pressure member, a revolving member the latter provided with lift receiving devices, an adjustable cup carrying element movably secured therein, a cam operating element extending within said device for holding a mass of lifts, a reciprocating member provided with projecting fingers for placing the lifts one on top of the other in stack formation, gluing means operating 100 in conjunction therewith, means for causing the same to become inoperative when the last lift is applied, devices on the pressure member for compressing the mass by the movement of the revolving member, means operable 105 on the stem of the presser foot for retaining any pressure the devices may apply, cams for releasing the pressure from the mass, other cams for extending the receiving device while the revolving member is in motion, 110 means for discharging the finished product while the receiving device is moving to its original or starting position.
27. The combination in a machine of the character described, of a driven and a non-driven member, coacting means for operating devices carried by each member, a drive element comprising an operating cam, a reciprocating member operated by the cam, a second reciprocating member yieldingly secured to and operating within the former, suitable driving means extending from the source of power to the latter, lift positioning fingers carried by the second reciprocating member, a glue applying device thereon, 120 125 130

means for rendering the gluing device inoperative, and means responsive to the movement of the driven member for restoring said glue operating devices to their original 5 or first position.

28. The combination in a heel building device comprising an intermittently driven and a non-driven member, of a plurality of lift receiving devices circumferentially arranged 10 on the driven member, said devices comprising a slidable base with a breast plate, an adjustable equalizer having a cupping means attached thereto, a cam operating element extending within said breast plate for holding 15 lifts in stacked formation to a predetermined height, a pressure foot, means carried by the non-driven member for exerting pressure on the presser foot, a friction means for holding such pressure while the driven member is 20 moving one step in its movement; means on said non-driven member for releasing the pressure simultaneously as the driven member and lift receiving device is moved a pre-

determined distance, separate means for completely disengaging the pressure device from 25 the lifts, and power means for starting and stopping said driven member at predetermined distances.

29. The combination in a heel building machine, of a pair of members, one being movable with respect to the other, receiving units on said movable member for lifts of heels to be built, a frame, means for advancing the movable member to dispose various receiving units beneath the frame, means carried by the frame for centering each lift on the receiving unit therebeneath, a power unit for actuating said frame to move it toward and away from each receiving unit, and an indicating device including a calibrated scale and 35 an indicating member in conjunction with said frame for determining the height of the heel to be built. 40

In testimony whereof I affix my signature.

WILLIAM E. SMALL.
